FASTENER FOR WINDOWS AND THE LIKE

Wilkie C. Warren and Buel F. Buckler,
Columbia, Mo.

Application March 7, 1940, Serial No. 322,712

3 Claims. (Cl. 292—254)

This invention relates to locks, and with regard to certain more specific features, to automatic locks, particularly for the vertical sliding types of windows, doors and the like.

5 Among the several objects of the invention may be noted the provision for both the upper and the lower sash of the conventional sliding window to be automatically locked into position when the window is closed, and for the automatic 10 locking of either sash when opened a specified or predetermined amount from its respective closed position; the provision of apparatus of the class described which is compact enough for use in connection with conventional counter-balanced, 15 sliding type windows and the like; and the provision of a device of the class described which is simple, automatic and trouble proof in operation. Other objects will be in part obvious and in part pointed out hereinafter.

20 The invention accordingly comprises the combination of elements, features of construction and the arrangements of parts which will be pointed out in the structures described hereinafter, and the scope of the application of which 25 will be indicated in the following claims.

In the accompanying drawing in which is illustrated one of the various possible embodiments of the invention,

Fig. 1 is an inside elevation of the invention; 30 Fig. 2 is an enlarged fragmentary view similar to Fig. 1, parts being broken away;

Fig. 3 is a horizontal section taken on line 3—3 of Fig. 2;

Fig. 4 is a view similar to Fig. 2 showing the 35 inside window raised partially and locked, and the outside window lowered partially and locked; and,

Fig. 5 is a vertical section taken on line 5—5 of Fig. 4.

40 Similar reference characters indicate corresponding parts throughout the several views of the drawing.

The invention relates to the automatic locking of the conventional counter-balanced type of 45 window sash, and the like, when it is brought to a closed or near closed position, also providing a means by which fresh air may be admitted to the room by raising the lower sash a short distance, or by lowering the upper sash a distance, 50 while still having the sashes firmly and automatically secured from being further lowered, or raised as the case may be from the outside. Adjustments of the sashes may be easily made from the inside by simply turning an operating handle, thereby releasing and freeing both windows 55 with one operation.

Referring now more particularly to the drawing, there is shown at numeral 21 a wall in which is a window frame 23 having an interior space 25 for movement of the counterweights

27 and ropes 29. Inside guides 31 are provided for lower and upper window sashes 33 and 35, respectively.

At the upper right-hand side of the lower sash 33, and at the lower right-hand side of the upper sash 35, are inserted respective bolt cases 9, each of which carries a cover plate 10 by means of which it may be fastened by screws 37 to the respective sash. Each bolt case 9 carries a 10 sliding bolt 11 normally biased outward by a coil spring 12. Each bolt 11 is interiorly shouldered so as to provide a stop against the inside of the respective cover 10, so as to limit outward movement. Each case 9 may be applied simply by drilling a hole in the sash and sinking the case therein. A small portion is mortised out to accommodate the cover 10 and the device is then fastened by means of screws 37. The simplicity of application of the bolts is thus apparent.

Opposite the upper part of the inside window and also opposite the lower part of the outside window are adjacent cases 1 having covers 2. The cases 1 are mortised into the guides 31 of the frame 23 and screws 39 hold down the assemblies.

Within each case 1 is a pair of guide pins 6 which slidably support a tumbler 4. Behind each tumbler 4 in its respective case 1 is a 30 rotary cam 3 mounted upon a common shaft 7 and arranged so that upon rotation of the shaft (counterclockwise in Fig. 2), the tumblers will be forced to the left, so that pairs of lugs 5 thereon become positioned flush in pairs of openings 41. Under these conditions any bolt opposite any opening 41 is prevented from intersecting the opening and will ride freely thereover and along the face of the cover 2, which being mortised is flush with the bottom of the respective 35 guide 31. Under such conditions the respective window carrying the respective bolt 11 may be opened or closed freely, the springs 12 being compressed at this time.

On the other hand, when the cam 3 is rotated 45 clockwise (an opening 43 permitting; see Fig. 4), the bias of any bolt which may be opposite any opening 41 will force it in the tumbler 4 (Fig. 4), thus causing the bolt 11 to intersect the respective opening 41 and lock the window.

Two openings 41 are carried in each case 1, and a pair of cases is used in adjacent guides 31. Thus, when the cam 3 is in the position shown in Fig. 4, the bolt 11 in the upper end of the lower sash 33 springs into the upper opening 41 of case 55 1; or into the lower opening 41 in the same case, when the lower window is lowered, as in Fig. 1. Likewise, the bolt 11 in the upper outer window will spring into the lower opening 41 in its respective case 1 when said outer sash 35 is low- 60

ered, and will spring into the upper opening 41 when the outer sash is raised to its shut position. Briefly, either window will then be automatically bolted (locked) shut if closed, and will be locked open a predetermined amount if moved toward open position.

There is a cam 3 in each case 1, and both cams are carried upon the shaft 7 which intersects both cases 1. A single control handle 8 is provided.

The device may be installed by having plates 2 mortised flush into the ways of the window frame at positions where the bottom of the upper sash and the top of the lower sash overlap. A hole is drilled through the frame to accommodate the cam-operating shaft 7, to which is secured handle 8.

At the proper position at the lower edge of the upper sash is mortised flush the barrel assembly 20 for the respective bolt, and the other barrel assembly for the other bolt is installed at the upper section of the sliding side of the lower sash.

The operation of the device for the above installation would be as follows:

25 When the upper sash for instance is raised to its extreme upper position, the respective bolt 11 will enter the respective upper hole 41, thereby securing the upper sash in this position automatically, until released. When the lower sash 30 is brought to its lowermost closed position, lower sash bolt 11, will enter the respective lower hole 41, thereby automatically securing the sash in this locked position.

To release the locked sashes from any locked position, operating handle 8 is turned counterclockwise, thereby moving shaft 7 which in turn operates cams 3 to force tumbler 4 carrying lugs 5 outward, thereby forcing bolts 11 from holes 41 and bringing the bolts to a position flush with 40 the surface of plates 2.

Either the lower or upper sash may then be raised or lowered as the case may be any amount less than the distance between holes 41, thereby permitting admission of fresh air from the outside with the knowledge that the sash will become locked when it is raised or lowered an amount equal to the distance of the above mentioned holes provided the handle 8 is turned clockwise to locking position. The operating handle 8 cannot be reached from the outside of the building.

If it is desired to open either window further than provided for above, the operator needs only to set the handle 8 to unlocked (counterclockwise) position and the window may then be further opened, or closed freely.

From the above it will be seen that any locking or unlocking operation serves to control locking of two double-hung windows. Only one control handle 8 is needed.

The mounting of the tumbler 4 is quite simple. The showing of parallel movement of both ends of the tumbler along the guides 6 is ideal and in practical operation the tumbler may pivot somewhat on the end opposite to the one at which the bolt operates.

In view of the above, it will be seen that the several objects of the invention are achieved 70 and other advantageous results attained.

As many changes could be made in carrying out the above constructions without departing from the scope of the invention, it is intended that all matter contained in the above description or shown in the accompanying drawing

shall be interpreted as illustrative and not in a limiting sense.

We claim:

1. A lock for a window which is slidable in a guide, comprising a member mortised into the guide and forming a recess provided with a lower and an upper opening in the guide, a tumbler in the recess movable toward and away from said openings and having portions movable to positions in said openings flush with the portion of 10 said mortised member which lies in the guide, said window having a recess, a bolt in said window recess normally biased outwardly therefrom and traversing said openings during window movement and being movable under its bias into 15 one of said openings in the absence of the flush portions of the tumbler, manual means for moving the tumbler toward the openings to force the bolt from any opening, and means whereby when said manual means is oppositely positioned, the 20 bias of the bolt in any opening ejects the flush portion of the tumbler therefrom to automatically lock the window.

2. A lock for double-hung windows sliding in adjacent guides comprising adjacent cases in the 25 two guides forming recesses each of which has a plurality of inlet openings, a tumbler in each recess movable toward and away from the openings therein and having portions adapted to be positioned in said openings flush with the exterior portion of the case which is in the respective guide, manual control means for operating the tumblers simultaneously, said windows having pockets for respectively receiving sliding bolts, means biasing the respective bolts out 35 of the openings, each bolt traversing the inlet openings of the adjacent case of the respective guide, each bolt passing over the respective openings when the respective tumbler is forced to flush position by the manual operating means but adapted to pass into one or another opening when the tumbler is not forced by said manual operating means, the openings in a given case being arranged for locking the respective window shut or in a predetermined open 45 position.

3. A lock for double-hung windows sliding in two adjacent guides, comprising adjacent cases mortised with external surfaces flush with the guide surfaces in the two guides and forming 50 recesses each of which has two inlet openings presented toward a window, a tumbler in each case movable toward and away from the openings therein and having portions adapted to be positioned in said openings flush with the external surface of the respective case, single manual control means for operating both tumblers simultaneously, each window having a pocket for respectively receiving a sliding bolt, means biasing the respective bolts out of the 60 respective pockets, each bolt traversing the inlet openings of the adjacent case in the respective guide, each bolt passing over the respective openings when the respective tumbler is forced to flush position by the manual operating means 65 but adapted to pass into one or another opening when the tumbler is not forced by said manual operating means, the openings in each case being arranged for locking the respective window shut or in a predetermined open position in 70 which the manual operating means cannot be manually reached from the outside of the windows.
